UNITED STATES PATENT OFFICE

2,436,942

SEAL FOR FLOATING ROOF TANKS

Edgar E. Shanor, Sharon, Pa., assignor to
General American Transportation Corporation,
Chicago, Ill., a corporation of New York

Application March 23, 1944, Serial No. 527,689

2 Claims. (Cl. 220—26)

1

This invention relates to improvements in storage tanks for oil, gasoline and other volatile liquids of the type in which the top or deck is not connected with the wall of the tank, but normally floats upon and is supported by the liquid in the tank.

In this type of tank there is an annular space between the tank wall and the deck, in which the level of liquid rises above the bottom of the deck due to the displacement of liquid by the deck. Unless this space is properly closed, undue evaporation of the liquid and consequent loss and possible explosion results. The closure means, however, must yield to the drifting of the roof and must make sliding contact with the inner surface of the tank wall to allow for the rise and fall of the deck when the tank is being filled or emptied.

The object of the invention is to provide a sealing or closure structure which meets the above requirements and at the same time remains gastight under all operating conditions.

A further object is to provide for the adjustability of the closure structure with respect to the level of the liquid in the annular space between the tank wall and the deck to minimize evaporation adjacent the sliding contact during summer temperatures and prevent freezing of moisture adjacent the sliding contact during winter temperatures.

Other objects of the invention will appear from the following description in connection with the accompanying drawings which illustrate one embodiment of the invention.

Referring to the drawings:

Fig. 1 is a vertical radial section through the tank wall and floating deck at one side thereof, showing in section the closure structure for the annular space therebetween adjusted for winter operation;

Fig. 2 is a similar section of the lower portions of the closure structure illustrating several relative positions thereof resulting from the drifting of the deck out of concentricity with respect to the tank, and illustrating further the closure structure adjusted for summer operation;

Fig. 3 is an inner face view of several adjacent suspension plates looking in the direction of the arrows on the line 3—3 of Fig. 1; and

Fig. 4 is a detail section on the line 4—4 of Fig. 1.

In the drawings, a fragment of a tank and floating deck is shown, but it is understood that tanks of this character are cylindrical in shape and have a continuous vertical wall A open at its top and having suitable reinforcement I around

2

its upper margin. The floating deck B is circular in shape and, if of the pan type shown in the drawings, comprises a flat bottom wall 2 and a vertical cylindrical wall 3 upstanding therefrom, this vertical wall generally being parallel with the wall of the tank. This invention is equally as well adapted to the types of floating decks which are provided with air chambers or pontoons. The deck is of less diameter than the tank, so that there is an annular space C between the tank wall and that of the deck. The deck is shown in the drawings as close to the top of the tank, so that substantially the full capacity of the tank is utilized; but it is understood, of course, that the deck which floats on the body of liquid in the tank rises and falls accordingly as the liquid level is raised or lowered in the tank. The deck, due to its weight, displaces the liquid which rises in the annular space C to a normal level above the bottom of the tank and indicated by the line 5.

The annular space C is closed or sealed by a flexible curtain or apron D of suitable material, such as asbestos fabric or synthetic rubber, which is gastight and fire resistant. This sealing or closure curtain extends continuously around the deck and bridges the gap between the deck and the tank wall. The upper inner edge of the curtain is clamped against the outer face of the deck wall 3 by means of the straps 6 and a series of bolts 7, so as to make the joint gastight and securely hold the curtain in place. The outer and lower margin of the sealing curtain is attached to and supported by a series of suspension members E in close relation to the inner face of the tank wall. These suspension members are in the form of rectangular plates which, for the most part of their area, are substantially flat, but which have their lower portions 8 curved on a suitable radius so that their outer face makes substantially a line contact 9 with the inner face of the tank wall, this line contact shifting slightly along the curve of the plates as the plates swing about their fulcrums when the deck drifts into eccentric relation to the tank wall. These plates are also preferably slightly curved transversely in the vicinity of the contact with the tank wall, so that they conform to the curvature of the tank wall and thus maintain as close contact throughout their width as possible.

The lower portion of the sealing curtain is curved to conform to the inner face of the curved portions 8 of the suspension members and are clamped against said faces by the curved clamping plates 10 which are secured to the portions

8 by means of the bolts 11. These clamping plates may be of any suitable width and as many as necessary provided, but it has been found that one clamping plate disposed in the center of each suspension member is sufficient to hold the closure curtain in close contact with the suspension members throughout their width.

The suspension members extend diagonally upward beyond the upper margin 12 of the wall 2 of the deck and are supported on fulcrum bolts or members 13 which permits them to swing radially. They are spaced apart sufficiently to allow freedom of radial movement without interference with each other; in fact, the spacing is such that fairly large openings are provided between the plates which render the suspension members themselves ineffective as a sealing or closure means for the annular space between the deck and the tank wall. Each suspension member is provided with a plate E' riveted on its inner face and extending downward to overlie the upper margin of the deck wall and serve as a watershed to minimize the possibility of water accumulation in the space between the member E and the sealing curtain D.

The fulcrum bolts are L-shaped and have their upper portions 14 turned radially outwardly beyond the wall 2 of the deck where they extend through holes 15 in the suspension members and holes 15a in the watersheds E'. Their outer end portions 16 are reduced to provide shoulders 17 against which the suspension members bear as fulcrums, the holes 15 being sufficiently large to provide for the free movement of the members. The members are retained on these fulcrum bolts against displacement by the pins 18. There are preferably two of these fulcrum supports for each suspension member to prevent them from any rocking movement in their own planes. The bolts are positioned adjacent the margins of the suspension members and are mounted on a continuous angle 19 which extends around the deck wall 2 and is secured by welding or otherwise to the inner face of the deck wall adjacent the upper margin thereof.

The vertical portions 20 of the fulcrum bolts extend through holes in the horizontal flange of the angle 19 and are threaded for the locking nuts 21, one of which is positioned on each side of the flange and screwed up tightly thereagainst to firmly hold the fulcrum bolt in position. This construction provides a considerable adjustment by which the suspension members E may be bodily raised or lowered to adjust the contact lines 9 of the suspension members with respect to the liquid level 5 in the annular space between the deck and the tank wall.

The lower portions 8 of the suspension members and the clamped lower portions of the closure curtain are always submerged in the liquid, but the position of the contact 9 with respect to the liquid level is important. During summer or warm weather temperatures, it is desirable to adjust the suspension members so that the contact line 9 of the suspension members coincide substantially with the liquid level 5 in the annular space, as indicated in Fig. 2. This leaves a minimum of liquid in the crevice 22 between the tank wall and the suspension member exposed to evaporation or fire. On the other hand, during the winter or freezing temperatures, the suspension members are bodily lowered so that the contact 9 is positioned considerably below the liquid level 5, as shown in Fig. 1, whereby a body of non-freezing liquid will be maintained

in the crevice 22 to prevent the freezing of moisture which may accumulate in the crevice and freeze the suspension members to the tank wall.

The upper portions of the suspension members E extend in their same plane above the fulcrum bolts and are acted upon by spring devices which urge the members yieldingly outwardly to maintain constant contact with the tank wall irrespective of the drifting of the deck. They also act as centering devices to restore the deck to concentricity with respect to the tank. One of these spring devices is provided for each suspension member. The spring device consists of the rod 23, the coil spring 24, and the supporting bracket 25. The outer end of the rod extends through a hole in the member E and has a T or cross-head 26 which bears against the outer face of the member E. The spring is mounted on the inner end portion of the rod and is positioned between the bracket 25 and a nut 27 which is threaded on the rod so that the spring may be placed under the proper degree of compression for the purpose. The outer end of the spring bears against a washer member 28 which has a bearing face 29 normal to the axis of the spring. This washer member is clamped to the bracket 25 by means of the bolt 30 and a nut 31. The bolt extends through an elongated slot 32 in the bracket 25, so that the position of the spring device can be adjusted vertically in the bracket 25 to conform to the vertical adjustment of the fulcrum bolts for the suspension members E. The base of the bracket 25 is turned horizontally and is secured to the horizontal flange of the angle member 19 by means of the bolt 33 and nut 34. The spring device for each suspension member E is preferably positioned substantially in the center thereof between the two fulcrum bolts.

I claim:

1. The combination of a storage tank for liquid having a vertical cylindrical wall, a roof deck floated upon the liquid in the tank and having a peripheral vertical wall annularly spaced from the tank wall, an annular series of plates disposed in said annular space and having their lower ends curved for contact with the tank wall and their upper ends extending above the deck wall, a pair of fulcrum bolts having outwardly turned upper ends extending through said plates for pivotally supporting the plates and having vertically disposed shank portions adjustably mounted on the inner side of said deck wall to adjust the contact of said plates with the tank wall relatively to the liquid level, a flexible continuous curtain secured at its inner edge to the deck wall and at its outer edge to the said plates below the liquid level, and spring devices acting upon said plates above said fulcrum bolts for yieldingly urging the plates in contact with the tank wall.

2. The combination of a storage tank for liquid having a vertical cylindrical wall, a roof deck floated upon the liquid in the tank and having a peripheral vertical wall annularly spaced from the tank wall, an annular series of plates disposed in said annular space and having their lower ends curved for contact with the tank wall and their upper ends extending above the deck wall, a pair of fulcrum bolts having outwardly turned upper ends extending through said plates for pivotally supporting the plates and having vertically disposed shank portions adjustably mounted on the inner side of said deck wall to adjust the contact of said plates with the tank wall relatively to the liquid level, a flexible continuous curtain secured

at its inner edge to the deck wall and at its outer edge to the said plates below the liquid level, spring devices acting upon said plates above said fulcrum bolts for yieldingly urging the plates in contact with the tank wall, said spring devices including rod members engaging the plates above their fulcrums, slotted brackets mounted on the deck wall, and springs on said rod members and positioned between the brackets and adjustable nuts on said rod members.
